DESIGN.

C. BOOZE.
WALL PAPER.

Patented Nov. 18, 1890.

No. 20,326.

UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 20,326, dated November 18, 1890.

Application filed September 27, 1890. Serial No. 366,383. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of intertwining vines and flowers of the Mexican rose arranged in a continuous wavy or serpentine line extending vertically over the surface of the paper. A rose in full bloom is 15 arranged at the extreme points of the wavy line, and leaves and flowers extend from the intertwining vines in various directions over the surface of the paper, as represented in the accompanying photograph.

The design is printed upon tinted paper of 20 any desired color.

What I claim is—

The design for wall-paper herein shown and described.

Witness my hand this 13th day of September, 1890.

CHARLES BOOZE.
